UNITED STATES PATENT OFFICE.

JOHN J. SOMMER, OF NORTH ATTLEBORO, MASSACHUSETTS, AND JAMES O. OTIS, ELLIS W. MACALLISTER, AND ALFRED B. LEMON, OF PROVIDENCE, RHODE ISLAND.

DESIGN FOR A BADGE.

Application filed July 14, 1923. Serial No. 6,776. Term of patent 3½ years.

To all whom it may concern:

Be it known that we, JOHN J. SOMMER, residing in North Attleboro, county of Bristol, and State of Massachusetts, JAMES O. OTIS, ELLIS W. MACALLISTER, and ALFRED B. LEMON, residing in Providence, county of Providence, and State of Rhode Island, citizens of the United States, have invented a new, original, and ornamental Design for a Badge, of which the following is a specification, reference being had to the accompanying drawing, forming a part thereof.

The figure is a face view of a badge, illustrating my new design.

We claim:

The ornamental design for a badge, as shown.

JOHN J. SOMMER.
JAMES O. OTIS.
ELLIS W. MACALLISTER.
ALFRED B. LEMON.
